US0D1003271S

(12) **United States Design Patent** (10) **Patent No.:** **US D1,003,271 S**
(45) **Date of Patent:** **** Oct. 31, 2023**

(54) **HEADPHONE**

(71) Applicant: **Shiping Hu**, Jining (CN)

(72) Inventor: **Shiping Hu**, Jining (CN)

(**) Term: **15 Years**

(21) Appl. No.: **29/879,984**

(22) Filed: **Jul. 15, 2023**

(30) **Foreign Application Priority Data**

Mar. 15, 2023 (CN) 202330120879.3

(51) **LOC (14) Cl.** **14-01**

(52) **U.S. Cl.**

USPC **D14/205**

(58) **Field of Classification Search**

USPC D14/205, 206, 226; D29/112; 2/209;

(57) **CLAIM**

The ornamental design for a headphone, as shown and described.

DESCRIPTION

FIG. 1 is a perspective view of a headphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the headphone that form no part of the claimed design.

1 Claim, 8 Drawing Sheets
